UNITED STATES PATENT OFFICE.

OTTO H. HARTMANN, OF CASSEL-WILHELMSHOHE, GERMANY, ASSIGNOR TO SCHMIDT'SCHE HEISSDAMPF GESELLSCHAFT M. B. H., OF CASSEL-WILHELMSHOHE, GERMANY, A CORPORATION OF GERMANY.

LOCOMOTIVE BOILER.

Application filed May 18, 1925, Serial No. 29,881, and in Germany June 10, 1924.

My present invention relates to locomotive boilers constructed in two sections for the generation of steam of two different pressures. More particularly, the high pressure section of the boiler embodies a fire box, the walls of which are formed by water tubes, while the low pressure section is constituted by a longitudinal boiler having smoke flues. In order to secure complete combustion of the fuel and a high efficiency, I interpose between the grate of the fire-box and the smoke flues of the longitudinal boiler, a channel-like chamber in open communication with the combustion chamber of the fire-box but closed at the sides as well as at the top and the bottom. In the preferred embodiment the hollow members, such as water tubes and the like, which form the walls of said channel, communicate with the high-pressure section, that is to say, with the water-tube fire-box, said channel virtually forming an extension of the fire-box. This novel arrangement increases the effective heating surface of the high-pressure boiler section, since the area of the channel is added to that of the water-tube fire-box, for the generation of high-pressure steam. The proportion of high-pressure steam to low-pressure steam is thus increased, and a low fuel consumption is obtained, approximating that of a boiler which produces high-pressure steam exclusively.

As applied to locomotives operating with steam of two different pressures, my invention offers a special advantage owing to the relative narrowness and length of the fire-box and combustion chamber. In the ordinary constructions, whenever a locomotive is to be exceptionally powerful, the large grate area required for this purpose is obtained by making the fire-box of considerable width, since the length of the grate is limited by the ability of the stoker to reach the farther portions thereof. A wide fire-box, however, provides a much smaller heating area exposed to the heat radiated from the furnace, than a narrow and correspondingly long fire-box. Thus, with a wide grate, the proportion of high-pressure steam to low-pressure steam is reduced, and becomes insufficient for the production of the maximum amount of high pressure steam.

A satisfactory and preferred embodiment of my invention is illustrated by the accom-

panying drawings, in which Fig. 1 is a longitudinal section of a locomotive boiler constructed according to the principle explained above, and Fig. 2 is a cross-section on line 2-2 of Fig. 1.

The high-pressure section of the boiler has a lower portion with longitudinal water chambers 1 and a rear transverse water chamber 2, and an upper portion comprising one or more steam and water containers 3, connected with said lower portion by water tubes 4 which cross each other as they extend upward from opposite sides of the fire-box. Between the rear flue sheet of the longitudinal low-pressure boiler section indicated at 5, and the grate 6 of the fire-box is located a combustion channel, the roof and sides of which are formed by water tubes 7 extending from the lower water chambers 8 to the upper container or containers 3. The bottom or floor of the combustion channel is formed by water tubes 9 connecting a transverse chamber 2' located at the front of the water-tube fire-box with a transverse pipe or chamber 10 located at the rear flue sheet of the longitudinal boiler 5. The combustion channel or chamber thus constructed affords the flame ample space for spreading and expanding, so that complete combustion will be obtained.

As seen in Fig. 2, the tubes 7 extend upwardly from the chambers 8, every alternate tube bent transversely to connect with the header 11 on the opposite side of the boiler, while the remaining tubes extend substantially vertically to the header on the same side of the boiler as the base of the tubes. Short tubes 13 extend from headers 11 to the interior of container 3, where they connect with a series of coils 19, which facilitate a transfer of heat from the headers 11 to the interior of the container 3. The floor of the combustion channel is formed by longitudinal tubes 9, which are connected to headers 11 by tubes 15. The steam evolved in the headers passes through pipes 13 to the coils 19, and the condensate is returned through tubes 14 to the chambers 8. Plugs 12 are removably inserted in the headers to facilitate cleaning and repair.

Various modifications may be made without departing from the nature of my invention as set forth in the claim.

I claim:

In a locomotive, a water-tube fire-box formed of vertical tubes and having a grate of normal maximum length for hand stoking, a drum communicating with the upper ends of the tubes of said fire-box to form therewith a high-pressure steam boiler, a fire-tube boiler in which low-pressure steam is generated by the combustion gases from said fire-box, said fire-tube boiler being independent of said high-pressure boiler, and

water-tubes forming a constricted combustion channel located between said fire-box and said fire-tube boiler, the upper ends of the tubes of said combustion channel being connected to said drum to transfer heat from the combustion channel to said drum. 15

In testimony whereof I have hereunto set my hand.

OTTO H. HARTMANN.
